UNITED STATES PATENT OFFICE.

SANFORD A. BARTLETT, OF WORCESTER, MASSACHUSETTS.

END-GATE.

SPECIFICATION forming part of Letters Patent No. 437,415, dated September 30, 1890.

Application filed June 5, 1890. Serial No. 354,331. (No model.)

To all whom it may concern:

Be it known that I, SANFORD A. BARTLETT, of the city and county of Worcester, and Commonwealth of Massachusetts, have invented 5 certain new and useful Improvements in Tail-Board Adjusters; and I do hereby declare that the following is a full, clear, and exact description thereof, reference being had to the accompanying drawings, and the letters of reference 10 marked thereon, forming a part of this specification, and in which—

Figure 1 represents a side view of one end of a wagon-body with my invention applied thereto, as will be hereinafter more fully described. Fig. 2 represents a top or plan view of a section of the parts shown in Fig. 1, as will be more fully described hereinafter. Fig. 20 3 represents a side view of a portion of the parts shown in Fig. 1 to illustrate a slight modification of the spring device, as will be hereinafter more fully described; and Fig. 4 represents a rear edge view of the tail-board-holding iron, as will be hereinafter described.

To enable those skilled in the art to which 25 my invention belongs to make and use the same, I will proceed to describe the same more in detail.

The nature of my invention consists of a simple, light, and yet durable device for holding the tail-board of a wagon or other similar carriage or cart in any desired position, in lieu of adjusting the same by means of the inconvenient straps and chains in common use for such purposes. Only so much of a 35 wagon-body is shown as is necessary to illustrate my invention, and the invention is to be applied to the end of the tail-board on each side of the wagon-body.

In the drawings, the part A is a section of 40 the bottom of the wagon; B, a section of one of the top rails of the side of the wagon; C, one of the bottom rails; D, the top rail of the tail-board E, which is hinged at a to the rear bottom rail of the body F of the wagon.

45 The body of the wagon and the tail-board hinged thereto may be made in the usual manner; but, in lieu of the old common straps and buckles or chains and hooks for adjusting and holding the tail-board E in a closed 50 or inclined position, I employ two tail-board adjusting and holding irons G—one at each rear corner of the body F of the wagon or

other carriage or cart—and a side view of one of these holding-irons G is shown in Figs. 1 and 3, and a top view in Fig. 2, and an edge view in Fig. 4 of the drawings.

The tail-board adjusting and holding iron G is made with a slot H extending nearly its whole length, as fully shown in full and dotted lines, Figs. 1 and 3 of the drawings, and it will be observed that the metal of the iron on the outer edge of the slot H is made with a series of curved holding hooks or rests b b b—one in this instance about midway and the other two near the bottom, all as fully shown in Figs. 1 and 3—while the metal on the opposite edge of the slot H is formed with slight pointed projections c c c, which are all above their respective hooks or rests b on the opposite edge of slot H, and the metal of the edge of the slot curves back slightly both above and below points c, as shown at d d d, and by which arrangement the necks of the corner-irons I on the upper corners of the tail-board can be moved down in slots H and 75 rested against either of the hooked or rest places b to give the tail-board a greater or less inclination, as indicated in dotted lines, Fig. 1.

Necks e have heads K, and the necks e and heads K can be cast with their respective corner-irons I. Neck e of one of the corner-irons is indicated by dotted lines, Figs. 1 and 3, and its length is only sufficient to permit the irons G to work easily between the side of its corner-iron I and head K on the outer end of 80 the neck e. I prefer to make the corner-irons I and the slotted irons G of malleable iron, since by this mode of construction they can be quite light and yet strong and durable.

M is an iron plate fastened to the upper rear 85 corner of the wagon-body, and through this a shouldered bolt N passes, its shoulder fitting against plate M, and between plate M and bolt-head the eye or projection G' is fitted to turn and swing, and as eye G' is made 95 with the part G the latter turns or swings when the tail-board E is moved back on bolt N as a fulcrum or center of motion.

To prevent the iron G from rattling, a spring is desirable to constantly press the lower end 100 of said iron forward, and in Figs. 1 and 2 one good arrangement is shown, where a spring P is fastened at one end in a lug P', projecting from plate M, while its upper spring or

free end *f* presses on the upper edge of eye-piece *G'*, back of its fulcrum *m*, as fully indicated in Fig. 1.

In Fig. 3 a modification of the spring arrangement is shown. A spring *Q* has its lower end fastened in a lug on the forward edge of iron *G*, while its upper or free end *g* is sprung forward and retained in that position by the grooved pin *R*, the end *g* of the spring working 5 around in the groove in pin *R*, which projects from plate *M*, and in this arrangement the tension of spring *Q* will be the same in whatever 10 position tail-board *E* may be.

When it is desired to have the tail-board *E* 15 dropped to a horizontal position, the necks *e* of the corner-irons *I* are allowed to slide down and rest in the lower ends *h* of the slots in the irons *G*, and when it is desired to let the tail-board drop down into a vertical position the 20 heads *K* are slid or moved through the loops *S* in the bottoms of the irons *G*, necks *e* passing through cross-slots *m* in the forward edges of the irons *G*, as indicated in full and dotted lines in the drawings.

25 The bolts *N* may serve to hold the upper

ends of the common corner-braces of the wagon-body.

Having described my improvements in tail-board adjusters for wagons and similar carriages, what I claim therein as new and of my 30 invention, and desire to secure by Letters Patent, is—

1. The within-described tail-board-adjusting iron *G*, provided with eye *G'* and slot *H*, the outer edge of which is provided with a series of holding hooks or rests *b*, and its opposite or inner edge with a series of projections *c*, while the bottom of iron *G* is provided with a cross-slot *m* and loop *S*, all as and for the 35 purposes set forth. 40

2. The combination, with the tail-board *E*, wagon-body *F*, and corner-irons *I*, provided with necks *e* and heads *K*, of holding-bolts *N* and tail-board adjusting and holding irons *G*, substantially as and for the purposes set forth. 45

SANFORD A. BARTLETT.
